UNITED STATES PATENT OFFICE

DANIEL NEAL, OF OTLEY, ENGLAND, ASSIGNOR TO JAMES WHITEHEAD, OF OTLEY,
ENGLAND

DEVICE FOR REMOVING THE VALVES FROM INTERNAL-COMBUSTION ENGINES

Application filed July 18, 1928, Serial No. 293,757, and in Great Britain August 16, 1927.

In connection with the cylinders of internal combustion engines and especially of those wherein the cylinders are arranged to be vertical or inclined and with the valves situated in the head of the cylinder, considerable difficulty is experienced in removing the valves from their positions or seatings to carry out the necessary cleaning and repairing of same. My invention consists in the production of means whereby, after the cylinder-head has been removed from the cylinder my improved devices may be applied to said head and made use of for removing the valves therefrom in a more expeditious manner than heretofore thus the process of cleaning and carrying out repairs is greatly facilitated.

In order that my said invention may be readily understood I have hereunto appended sheets of drawings illustrative thereof to which by figures and letters reference is made in the following description:—

Fig. 1 is a plan of a cylinder head showing the application of my improved devices.

Fig. 2 is a sectional elevation of the parts shown by Fig. 1 and with my devices shown in position prior to commencing the compression of the spring.

Fig. 3 is a similar view to Fig. 2 but shows only one valve and with my devices in position when compressing the spring.

Fig. 4 is a plan of the valve spindle and the plate or washer which takes over the end of the spring.

Fig. 5 is a plan showing the formation of the several parts of my improved device.

Fig. 6 is an elevation of the parts shown by Fig. 5 said parts being shown in their respective positions as when used on a valve spindle which is at an angle to the axis of the cylinder as shown by Figs. 1, 2 and 3.

Fig. 7 is a similar view to Fig. 6 but shows the positions of the parts when the axis of the valve spindle is parallel to the axis of the cylinder.

In carrying my invention into effect I make use of a base member 2 which is formed to fit against the detached head 3 of the cylinder as shown by Figs. 2 and 3. The head of the screw 4 may be gripped by the jaws of a vice in order that the head 3 and the base

member 2 may be firmly held in position. Upon the said member or plate 2 I secure a block 5 by means of the screw 5 so that the upper surface *a* of this block 4 (in the arrangements shown by Figs. 2, 3, 4 and 5) is inclined to the axis of the cylinder but is at right angles to the axis of the valve spindle 6.

The base member 2 has its outer end 2^a formed so that a slot *b* may be made therein in order that a detachable arm 7 may be inserted through the slot *b* and then be turned into position to enable its notches 7^a to span or take over the two side parts of the slot *b* as shown by Figs. 2 to 7 inclusive.

This arm 7 has a series of holes or openings *c* formed in it so that a pivotal pin 8 may be inserted in any one of same to suit the requirements of the hand lever 9 when this is being used in connection with a smaller or larger cylinder head 3 as will be understood.

Pivoted upon the pin 8 (which is detachable) is a lever 9 in which are also made openings *d* for the pin 8 so that the said lever 9 may be adjusted according to the requirements of any particular size of head in connection with which it may have to be used.

The hand lever 9 has at its opposite end to its handle a bifurcation 9^a which will span the spindle 6 of the valve 6^a and will reach over the annular member or washer 10 which takes over said spindle 6^a.

This washer or annular member 10 is of well known formation and is held upon the spindle 6 of the valve 6^a by the coupling bush 11 taking into a groove 6^b in said spindle 6 which is also of well known formation.

The bush 11 is made in halves so that it may be detachable from the groove 6^b in the spindle 6 when the annular member 10 is forced down over said spindle 6 by the lever 9 and as shown by Fig. 3. This action of the lever 9 compresses the springs 12 in order that same may be held clear of the divided bush 11 as shown by Fig. 3 in order that while in this position the two halves of the bush may be removed. In Fig. 3 one half of the bush 11 is shown in position while the other is removed therefrom.

After the removal of the divided bush 11

the hand lever 9 may be released so that the springs 12 are freed and (after the base 2 has been removed from the jaws of the vise) the valve 6^a may be taken from the head 3 by withdrawing the spindle 6 of said valve after removing all the parts from the vise.

In cases where the valves 6^a and their spindles 6 are parallel to the axis of the cylinder in connection with which they have to operate I then make use of a block 5^a which is at right angles to the axis of the spindle 6 with which it has to operate and in such case I then turn the bar 7 with the lower end shown by Fig. 6 wherein the notches 7^a are formed so that said bar may have its notches 7^b brought through the slot b of the base member 2 as shown by Fig. 7, the operations of the other parts being the same as is heretofore described. As is hereinbefore explained the divided bush 11^b is of well known construction and is used in connection with the annular member 10 for readily fixing same upon the spindle 6 of the valve 6^a, said spindle being actuated by the oscillating arm 12^a in well known manner.

The slot x (Fig. 5) which is made in the member 2 enables the adjustment of the block 5 in any position that a larger or smaller head 3 may necessitate.

Such being the nature of my said invention what I claim is:—

In devices for removing valves for internal combustion engines, a base piece having adjusting slots as described, a block mounted to be adjusted along one slot, a lever-support formed to be adjusted along the other slot in the base piece, said lever-support having a series of openings formed in it to permit the adjustment of the hand lever thereon, a hand lever having bifurcations at one end and a handle at the other end with a series of pivotal openings to permit the adjustment of said hand lever and means for pivoting said lever upon its support.

DANIEL NEAL.
